UNITED STATES PATENT OFFICE.

OSWALD HELLER, OF HALENSEE, NEAR BERLIN, GERMANY.

PLANT FOR UTILIZING THE SENSIBLE HEAT OF HOT COKE.

Application filed September 29, 1924, Serial No. 740,587, and in Germany October 3, 1923.

This invention relates to a plant for raising steam by means of heat obtained from vapours formed by quenching coke in a closed receptacle. It is already known to 5 pass these vapours into a heat exchanger or boiler containing clean water from which pure steam is thereby produced.

My invention consists in the improvements relating to the said boiler for the efficient 10 exchange of heat between the said vapours and clean water, as particularly set forth in the appended claim.

In the accompanying drawing, a plant embodying the invention is shown diagrammatically, by way of example.

The coke K contained in the movable receptacle 1 is brought into a quenching casing 2 having a gas tight door and provided with a fire- and acidproof lining. As shown in 20 dotted lines in the drawing annexed, the coke receptacle with the hot coke is carried by the intermediary of a suitable carriage 1^a over the open quenching casing 2 into which the receptacle is then lowered by means of 25 a lift not shown in the drawing and suitably arranged on the carriage 1^a. After the cover 2^a is closed gas-tight the coke is sprayed with water through the perforated pipe 2^b, steam containing sulphurous acid and water 30 gas being formed. To prevent the same from attacking the interior of the chamber 2, it is lined with acidproof brickwork. A safety valve 2^c arranged on the casing 2 opens automatically when the pressure of 35 the said steam rises too high. The steam generated in the casing passes through the outlet 2^d and enters the dust separator 3 where it meets with the baffle plate 3^a so that the direction of the steam is changed and 40 the coarser cokedust is thereby caused to fall down to the bottom of the separator 3. From the said separator the steam after having passed a check valve 4 enters a column filter 5 filled with suitable material 5^a, where the 45 fine dust will be retained. The steam thus freed from dust now flows into the boiler 6 having heating tubes 6^a of acidproof material.

In the plant now being described, the 50 steam generated by the coke quenching has a pressure of approximately 12 atmospheres, and since, by means of the said plant, it is desired to generate steam of 5 to 6 atmospheres in the boiler 6, it is necessary that a 55 temperature drop of 190° to 160° C. should exist between the inlet and outlet ends of

the heating tubes 6^a. With this temperature drop, it is possible to extract the heat from the quench steam by means of a relatively small heating surface and to condense the 60 said steam to water at 160° C. while producing the steam of 5 to 6 atmospheres pressure in the boiler 6. The last mentioned steam contains no acid and no gases and can be utilized for driving a steam engine or for 65 any other purpose.

The water of condensation together with air and water-gas flows from the tubes 6^a through a pipe 7 to a heat exchanger or feed water heater 8 in which the feed water is 70 heated by the hot water of condensation passing through the tubes 8^a. The heat exchanger or feed heater 8 is essentially positioned as shown in the drawing, that is, below the steam generator 6^a, and the said 75 exchanger or heater 8 must also have the inlet of the pipe 7 positioned at the bottom and the overflow 8^c at the top, these conditions being necessary in order to obtain a hydrostatic head in the exchanger or heater 80 8 opposing the pressure in the coke quenching casing 2.

The desired temperature drop from 190° C. to 160° C. in the tubes 6^a is obtained by 85 providing an adjustable pressure-maintaining device at one end of the plant, the said device consisting of an adjustably loaded release valve 8^b which allows the escape of air and water gas from the exchanger or heater 8, and of a water or condensed-steam chamber 9 which communicates with the top of the exchanger or heater 8 by the aforesaid overflow 8^c. The water chamber 9 also communicates at the bottom with a water pipe 90 leading to a discharge channel 10, the communication between the chamber 9 and channel 10 being controlled by a valve 9^a which is opened and closed in accordance with the water level in the chamber 9 by a float as 95 shown.

In the plant described, the release valve 8^b is set so as to open and let off air and water gas only when the pressure in the exchanger or heater 8 rises above 12 atmospheres. In this manner, a pressure is built 105 up in the coke quenching casing 2, and, furthermore, the water of condensation flows past the valve 9^a when the same is raised by its float, the water from the chamber 9 ascending the aforesaid water pipe to the 110 channel 10 under the action of the 12 atmospheres pressure existing in the top por-

tion of the chamber 9 in common with the top of the exchanger or heater 8.

What I claim is:—

A plant for generating pure steam at a pressure above atmospheric by quenching glowing coke comprising, in combination, a gas-tight quenching receptacle for the coke, means for admitting water to the coke in the receptacle to produce steam and water-
gas and other vapours under pressure, a steam boiler, flue means for said boiler in communication with the quenching receptacle whereby the heat in the vapours obtained from the quenching receptacle is directly absorbed to generate the pure steam at super-atmospheric pressure, a heat exchanger, means for passing condensed steam and water gas and other vapours from the flue means of said boiler to the bottom of

said heat exchanger, release valve means on the top of said heat exchanger to permit the escape of water gas and other uncondensed vapours at a pre-arranged pressure, overflow means at the top of said heat exchanger for water of condensation, means for supporting said heat exchanger below said boiler to obtain a hydrostatic head in said exchanger opposing and consequently enabling the building up of a pressure in the coke quenching receptacle, a water chamber into which the overflow means from said heat exchanger leads, and float-operated valve means controlling the escape of water from said chamber in accordance with the varying water level therein.

In testimony whereof I have signed my name to this specification.

OSWALD HELLER.
